UNITED STATES PATENT OFFICE.

ADAM GOOD, OF CLAFLIN, KANSAS.

LIQUID-AGITATOR.

No. 805,458.

Specification of Letters Patent.

Patented Nov. 28, 1905.

Application filed October 27, 1904. Serial No. 230,271.

To all whom it may concern:

Be it known that I, ADAM GOOD, a citizen of the United States, and a resident of Claflin, in the county of Barton and State of Kansas, 5 have invented a new and Improved Liquid-Agitator, of which the following is a full, clear, and exact description.

My invention has for its object the improvement of devices for agitating liquids for various purposes—such as mixing liquids, churning butter, &c. It may also be used for aerating milk and other liquids.

My invention further consists in the construction and combination of parts, as will be 15 more fully described in the detailed description appended hereto and definitely set forth in the claim.

Reference is to be had to the accompanying drawing, forming a part of this specification, 20 in which the figure is a side elevation of my invention complete with part in section.

Upon a base 1 is mounted a cylindrical air-compressor 2, with openings in the cylinder-heads 3 4 and connections 5 6 made thereto. 25 These connections communicate with intake-valves 7 8, which act only in one direction. They also communicate with similar valves 9 10, which act in the opposite direction and allow air to pass only when under compression sufficient to open said valves. The valves 7, 8, 9, and 10 are ordinary check-valves and are well known in the art to which they belong. The valves 7 and 8 are in immediate communication with a common supply - pipe 11. 30 An oil-cup 2^a is provided for lubricating the air-compressor.

In the preferable form of my compressor I use a hand-lever 12, connected by a pivot-pin 13 to a link 14, which is pivotally mounted on 40 the cylinder 2. The lower end of the lever 12 is connected by a pivot-pin 15 with a piston-rod 16. By this means a powerful stroke can be given the piston in the compressor. By means of holes 13^a in the lever 12 and 45 holes 13^b in the links 14 the pivot-pin 13 may be so adjusted as to vary the leverage of the hand-lever 12.

Supported above the base 1 is a receptacle 17, which is adapted to contain the liquid to 50 be acted upon. This receptacle may, however, be mounted upon a separate support if so desired. It consists, preferably, of sheet metal and has a cone-shaped bottom 18 and is provided with a cover 19 for excluding dust, 55 dirt, &c. The side of the receptacle is provided with an outlet 20, having a valve 21

therein for closing the same. At a higher point in the side of the receptacle is a spigot 22 of any ordinary construction. To indicate the height of the liquid in the receptacle when 60 the same is made of sheet metal or other opaque material, a gage-glass 23, mounted in settings 24, is connected at the lower point of the receptacle and also at a point above the same, so that all heights of liquid are indicated. If desired, this receptacle may be made entirely of glass, so that the action of the air upon the liquid is readily seen.

At the apex of the cone-shaped bottom 18 are connected two pipes 25 25^a, provided, respectively, with check-valves 26 26^a. Above these check-valves are located T's 27 27^a. To these T's are attached outlets 28 28^a 29 29^a. Each check-valve 26 26^a is so arranged that it will allow air to pass upward into the receptacle 17, but will prevent a downward flow of the liquid when the pressure of the air is removed. Each pipe 25 25^a is directly connected with the air-compressor by means of connections to the pipe 11. Hand-valves 30 80 30^a 31 31^a are used for removing the liquid from the receptacle 17.

Between the air-compressor and the pipe 25 on the pipe 11 is located a thermometer 32, a pressure-gage 33, and relief-valve 34. The 85 thermometer is intended to record the temperature of the air under compression, the gage indicates the pressure of the same, and the relief-valve can be adjusted for the amount of pressure required for the proper action of 90 the air upon the liquid.

By so locating the pipes as to introduce air into the liquid at the bottom thereof one or more streams of air are forced directly into the liquid, and there is no loss of pressure due 95 to the air striking the sides or bottom. The advantage of having the cone-shaped bottom is that the air expands more readily through all parts of the liquid, and thus produces the effect desired more quickly and in a more efficient manner. It is not absolutely necessary, however, to have this bottom cone-shaped, since other shapes will act well enough in many instances.

In operating upon some liquids the agitation required is quite great, while in others it is slight, and too great an agitation is objectionable. For this reason the relief-valve 34 is used, and by means of it the pressure required for the particular liquid to be acted 105 upon can be nicely adjusted.

While the above is a description of one of

the forms of my invention, I do not wish to be limited to the precise details set forth therein, but only in so far as indicated by the claim.

- 5 Having thus described my invention, I claim as new and desire to secure by Letters Patent—

In a liquid-agitator, the combination of a cylinder and a piston operating therein, valve-controlled air-inlets at opposite ends of said cylinder, valve-controlled discharge-pipes also at opposite ends of said cylinder, connections between the inlet and discharge pipes,

means for establishing communication between said connections and the ends of said cylinder, a receptacle for a liquid, and a pipe 15 connected with both discharge-outlets and with said receptacle for said liquid.

In testimony whereof I have signed my name to this specification in the presence of two subscribing witnesses.

ADAM GOOD.
